UNITED STATES PATENT OFFICE.

ANDREW J. JOHNSON, OF CUYAHOGA FALLS, OHIO.

FIRE-ESCAPE.

SPECIFICATION forming part of Letters Patent No. 286,306, dated October 9, 1883.

Application filed April 23, 1883. (No model.)

To all whom it may concern:

Be it known that I, ANDREW J. JOHNSON, of Cuyahoga Falls, Summit county, Ohio, have invented a new and useful Improvement in 5 Fire-Escapes, of which the following is a specification.

My invention relates to the manner of controlling the speed in unwinding the wire or cord from the reel by means of a governor 10 whose centrifugal force presses a friction-shoe against the inner circumference of a flange on the reel.

In the drawings forming a part of this specification, Figure 1 is a front view with face-plate removed, and Fig. 2 is a section.

Reel *a*, on which the wire cord is wound, is keyed on shaft *i* and inclosed in case *b*. Shaft *i* is supported by and rotates in case *b*, which is formed with a removable face-plate, *b'*, and a suitable opening, *o*, in its circumference, through which the cord passes in unwinding. Reel *a* has an annular flange, *a'*, on one side, forming a depression or cavity which contains the mechanism for regulating the rotation of the reel. The inner circumference of flange *a'* is toothed, and it is also formed with an annular V-shaped groove, *c*. Wheel *n* turns on a pin, *n'*, supported by face-plate *b'*. Pinion *m* is attached to spider *f*, and is loose on shaft *i*. The outer ends of the arms of spider *f* are slotted to receive governors *s* and support them crosswise of the arms. Wheel *n* connects the toothed flange *a'* with pinion *m*, and rotates the latter with spider *f* and governors *s* in a direction opposite to the rotation of reel *a*. Governor *s* is pivoted to the spider-arm at one end, and is weighted with a weight or ball, *s'*, at the other end. It is formed with a nib, *s''*, which enters a notch in shoe *e*. The 40 latter fits in the V-shaped annular groove *c*.

When a person desires to descend from an upper story of a building or other height by means of my herein-described fire-escape, he should first make fast the outer end of the wire cord to some suitable object that will sustain his weight. Then case *b* should be strapped to his body through eye *h*. He may then descend. The rotation of reel *a*, caused by the unwinding of the cord, rotates spider *f* rapidly in the opposite direction, and the centrifugal force thus developed throws outward governors *s*, which press shoe *e* in the annular groove *c*, and thus by friction of the shoe in the groove check the speed in descending.

If preferred, more than one wheel *n* may be 55 employed to connect the toothed flange *a'* with pinion *m*, and as many governors *s* may be used as may be deemed desirable.

The wire cord may be wound on reel *a* by inserting a key in socket *w* and turning shaft 60 *i* with the reel.

Flange *a'* may be formed with a cylindrical surface, instead of groove *c*, for the shoe *e* to bear against; but the V-shaped groove is 65 deemed preferable.

I claim as my invention—

1. The reel *a*, formed with a toothed annular flange, *a'*, in combination with case *b*, shaft *i*, toothed wheel *n*, pinion *m*, spider *f*, governor *s*, and shoe *e*, substantially as described. 70

2. The reel *a*, formed with a toothed annular flange, *a'*, having an annular V-shaped groove, *c*, in combination with case *b*, shaft *i*, toothed wheel *n*, pinion *m*, spider *f*, governor *s*, and shoe *e*, substantially as described. 75

ANDREW J. JOHNSON.
